(57) **CLAIM**

I claim the ornamental design for a helmet holder, as shown and described.

DESCRIPTION

FIG. 1 is a perspective view of my design for a helmet holder;

FIG. 2 is a top view of my design for a helmet holder;

FIG. 3 is a right elevational view of my design for a helmet holder;

FIG. 4 is a left elevational view of my design for a helmet holder;

FIG. 5 is a bottom view of my design for a helmet holder;

FIG. 6 is a rear view of my design for a helmet holder;

FIG. 7 is a front view of my design for a helmet holder;

FIG. 8 is a perspective view of my design for a bottom portion of a helmet holder;

FIG. 9 is a top view of my design for a bottom portion of a helmet holder;

FIG. 10 is a right elevational view of my design for a bottom portion of a helmet holder;

FIG. 11 is a left elevational view of my design for a bottom portion of a helmet holder;

FIG. 12 is a bottom view of my design for a bottom portion of a helmet holder;

FIG. 13 is a rear view of my design for a bottom portion of a helmet holder;

FIG. 14 is a front view of my design for a bottom portion of a helmet holder;

FIG. 15 is a perspective view of my design for a top portion of a helmet holder;

FIG. 16 is a top view of my design for a top portion of a helmet holder;

FIG. 17 is a right elevational view of my design for a top portion of a helmet holder;

FIG. 18 is a left elevational view of my design for a top portion of a helmet holder;

FIG. 19 is a bottom view of my design for a top portion of a helmet holder;

(Continued)

FIG. 20 is a rear view of my design for a top portion of a helmet holder; and,
 FIG. 21 is a front view of my design for a top portion of a helmet holder.
 The broken lines shown in the drawings represent portions of the helmet holder that form no part of the claimed design.
